UNITED STATES PATENT OFFICE.

DAVID FLAGG, OF GRAYLING, MICHIGAN, ASSIGNOR OF ONE-FOURTH TO
MARIUS HANSON, OF GRAYLING, MICHIGAN.

CAR BROOM OR BRUSH HOLDER.

SPECIFICATION forming part of Letters Patent No. 730,206, dated June 2, 1903.

Application filed March 31, 1903. Serial No. 150,478. (No model.)

To all whom it may concern:

Be it known that I, DAVID FLAGG, residing at Grayling, in the county of Crawford and State of Michigan, have invented a new and Improved Car Broom or Brush Holder, of which the following is a specification.

My invention relates to that class of broom or brush holding devices employed on cars for removing snow and ice and otherwise cleaning and scraping car-tracks; and it refers more particularly to that class of devices especially designed for use on hand-cars. Ordinarily hand-cars are provided with a bracket-iron in which the broom-shank is held by a set-screw or wedge in such manner that it requires the adjustment of the set-screw or wedge to hold the broom either in an operative or in an inoperative condition, which from experience I have found is very objectionable, for the reason that it is often necessary to shift the broom many times a day, and on account of the necessity of frequently moving the hand-car off the track quickly out of the way of an approaching train the car-men have not sufficient time to set the broom to its elevated or inoperative position, thereby often breaking off the broom, as well as dragging it over the ground.

My invention seeks to overcome the several objections noted, and it comprehends in its generic nature a bracket adapted to be secured to the car at any desired point and provided with a transversely-rockable member having a socket to receive the broom-shank and hold it against a swing movement with the longitudinal plane of the car-track—that is to say, in a rigid sweeping position—and arranged to permit the broom being instantly swung to a horizontal position by simply pressing down the upper or projected end of the broom-handle and to automatically hold the said broom to such elevated position.

In its more complete nature my invention includes a peculiar construction of broom-holding socket and adjustable clamp devices for holding the broom at the desired elevations and for permitting the vertical swing of the broom to its upper or lower positions without the necessity of changing the adjustment of the clamping devices; and in its still

more subordinate features my invention consists in certain details of construction and peculiar combination of parts, all of which will hereinafter be fully described, and specifically pointed out in the appended claims, reference being had to the accompanying drawings, in which—

Figure 1 is a perspective view of a portion of a hand-car with my invention applied. Fig. 2 is a front view of the same, the dotted lines showing the broom swung up to its inoperative position. Fig. 3 is a longitudinal section of the same on the line 3 3 of Fig. 2. Fig. 4 is a transverse section thereof on the line 4 4 of Fig. 3. Fig. 5 illustrates the several parts constituting my holder separated.

In the practical construction my invention comprises a bracket A, having a head portion a, adapted to be bolted to the car-frame C at the desired point—for example, at the front end of the side beams c of the said frame—and which is integral with an outwardly and downwardly inclined arm a'; whose lower end terminates in a tubular head a², which forms the bearing for a bolt B.

D designates a tubular member held in alignment with the bearing a² at the front edge thereof, in which the headed end b of the bolt B seats, and the said member d has an integral inwardly-projected portion d', vertically apertured, as at d², to form a socket to receive the short shank-handle f of the broom or scraper F.

By referring now more particularly to Fig. 4 it will be noticed the member D has its inner half d^x reduced and the said reduced portion projected radially with respect to the axis of the bolt B, and the inner edge of the portion d^x terminates with a threaded boss d⁵, disposed centrally on the socket d'.

The clamp member G co-operates with the part d', and the said member G has upper and lower extensions g g, adapted to straddle the member d', and a socket g' to fit over the boss d⁵, and the inner faces of the extensions g g are concaved, as at g^x, to oppose the concaved surfaces d⁶ d⁶ of the fixedly-held socket member, whereby when forced inwardly by the clamp-screw H the said faces g^x and d⁶ will firmly grip the broom-handle,

as shown, it being manifest that by reason of the peculiar construction of the clamp device referred to the broom may be readily removed from its socket or adjusted therein without removing the part G, it being only necessary to properly loosen or turn back the clamp-screw H.

The meeting faces of the members D and a^2 have interlocking portions in the end of a pair 10 of diametrically oppositely disposed V-shaped ribs 5, formed on the member a^2 , and a series 15 of radially-disposed V-shaped grooves 6 on the inner face of the member D, adapted to engage with the ribs 5 and to normally hold the member D interlocked with its mate a^2 when the ribs 5 and a corresponding set of 20 grooves 6 register. A stout coiled spring S is mounted on the outer end of the bolt B between the washer and nut B⁶ and the adjacent face of the member a^2 , as clearly shown in Fig. 3.

By arranging the parts a^2 and D as shown and described the member D can be freely rotated on the bolt B when pressure sufficient 25 to overcome the tension of the spring is applied, and by proper interlocking of the ribs 5 and the grooves 6 the socket portion on the member B can be positioned at a vertical or in a horizontal plane, and as the member D 30 is rigidly held against movement in the direction of the length of the bolt B it follows that the broom is thereby held rigid with respect to the holder when adjusted to its upper or lower positions. As the member D is 35 freely rotatable on the bolt B, it is manifest that by merely pushing or pulling the broom-handle in the direction of the arrow in Fig. 2 the broom can be instantly turned to its inoperative position under the car-frame, and 40 by pushing the handle in the reverse direction the broom can be quickly turned to an operative position.

I am aware that broom-holders, track-cleaners, &c., have heretofore been provided in 45 which the broom is held to be swung up out of contact with the ground or the rails; but so far as I know it has been required that clamp or nut devices be first adjusted to admit of such movement of the broom.

50 My invention differentiates from what has heretofore been done in this art, so far as I know, in providing a bracket having a socket member arranged to admit of freely moving the broom transversely and to the track-rail 55 and to rigidly hold the broom from swinging in the longitudinal direction of the rail and also in the detailed arrangement of the several parts hereinbefore pointed out.

Having thus described my invention, what

I claim, and desire to secure by Letters Patent, is—

1. A broom-holder of the class described, comprising a bracket adapted to be attached to the car-frame, a socket member mounted on the bracket to rotate transversely with respect to the car-rail, means on said socket member for clamping a broom-shank in the socket, and a separate means for automatically locking and holding the socket member to transversely-adjusted positions. 65

2. An improved broom-holder comprising a bracket having a tubular head; a clamp device having a tubular head adapted to be held in alinement with the tubular bracket member, a bolt seating in the tubular portions of the bracket and the clamp, said clamp member being transversely rotatable with respect to the bracket, means mounted on the bolt and the tubular portions of the bracket and the clamp for automatically locking the 80 clamp member to its different adjustments, the said clamp member having a broom-socket in a plane at right angles to the bolt-aperture, and means for securing the broom-handle in the said socket, as specified. 85

3. A broom-holder of the kind described; comprising a bracket adapted to be secured to and projected from a car-platform; a broom-clamp pivotally mounted on the bracket and laterally adjustable with respect to the said 90 bracket, automatically-actuating means cooperatively joined with the clamp and the bracket for holding the clamp and the broom at its vertical or horizontal adjustments, said clamp being rigidly held from movement in 95 the longitudinal plane of the bracket, as specified.

4. In a broom-holder of the character described, the combination with the bracket, said bracket comprising an attached head at 100 one end and a tubular portion at the other end having radial ribs on one face, a clamp consisting of a tubular member d^2 having radial grooves to engage the ribs on the tubular portions of the bracket, a headed bolt 105 adapted to be received in the apertures of the tubular bracket and clamp members, a tension-spring for drawing the bolt to interlock the aforesaid V-shaped grooves and ribs, the said clamp member including a broom-socket at right angles to the bolt-aperture, 110 said socket including a detachable grip portion, and means for clamping the said grip portion against the broom-handle, as specified. 115

DAVID FLAGG.
